UNITED STATES PATENT OFFICE

MORTIMER C. LYDDANE, OF YONKERS, NEW YORK, ASSIGNOR TO DAVID H. ZELL, OF BROOKLYN, NEW YORK

DESIGN FOR A VANITY CASE

Application filed July 16, 1929. Serial No. 32,072. Term of patent 7 years.

To all whom it may concern:

Be it known that I, MORTIMER C. LYDDANE, a citizen of the United States, residing at Yonkers, in the county of Westchester and State of New York, have invented a new, original, and ornamental Design for Vanity Cases, of which the following is a specification, reference being had to the accompanying drawing, forming part thereof.

Fig. 2 is an edge view,

Fig. 3 is an end elevation, and

Fig. 4 is an elevation of the opposite end of the case.

The dominant feature of my new design consists in the exterior contour or shape of the vanity case shown.

I claim:

The ornamental design for a vanity case, as shown and described.

MORTIMER C. LYDDANE.
